UNITED STATES PATENT OFFICE.

ROBERT MAXWELL, OF PERU, KANSAS, ASSIGNOR OF ONE-HALF TO HENRY C. DRAVER,
OF KANSAS CITY, MISSOURI.

FEED-PACKER.

1,003,006.

Specification of Letters Patent. Patented Sept. 12, 1911.

Application filed August 19, 1909. Serial No. 513,712.

To all whom it may concern:

Be it known that I, ROBERT MAXWELL, a citizen of the United States, residing at Peru, in the county of Chautauqua and State 5 of Kansas, have invented certain new and useful Improvements in Feed-Packers, of which the following is a specification.

This invention relates to feed packers, and my object is to produce apparatus of this 10 character which will operate efficiently, reliably and expeditiously, and by which feed may be packed at the desired density.

With this general object in view and others as hereinafter appear, the invention 15 consists in certain novel and peculiar features of construction and organization as hereinafter described and claimed; and in order that it may be fully understood reference is to be had to the accompanying drawings, in which;

Figure 1, is a central vertical section of the lower portion of a feed packing apparatus embodying my invention with the movable parts in their initial positions. Fig. 2, 25 is a side elevation of the complete apparatus on a smaller scale than Fig. 1. Fig. 3, is an enlarged cross section taken on the line III—III of Fig. 2. Fig. 4, is a top view of the upper part of the apparatus. Fig. 5, 30 is a side view of the upper part of the extension rod of the machine in its elevated and inoperative position.

In the said drawings, 1 indicates a chute leading through a floor 2 to a bin 3 mounted 35 upon a suitable frame 4 and provided with a cylindrical discharge spout 5 provided, by preference, with an external groove 6 and with a plurality of inwardly projecting pins or shoulders 7 above said groove as a means 40 of limiting the downward movement in the spout of an inverted hollow truncated cone 8, which in practice forms a tapering or diminished mouth for the spout. Underlying and of slightly larger diameter than the 45 spout and suitably supported is a cylindrical casing consisting of a semi-cylindrical stationary portion 9 and the semi-cylindrical hinged door 10, any suitable latch mechanism 11, not detailed because of its unimportance, being employed to secure the door in 50 its closed position.

12 is a sack adapted to be fitted over the lower end of the spout 5 when the door 10 is opened and secured by a clamping ring

12^a or equivalent device, in the external 55 groove of the spout.

13 is a reciprocatory rod arranged centrally in the spout and extending up through the bin and floor 2 as well as other floors if desired, in fact it is preferred that said rod 60 shall be of sufficient length to extend up through the topmost floor of the mill equipped with the apparatus, the rod being guided near its lower end in a cross bar or other guide 14 and near its upper end in 65 any suitable manner, not shown, cross bar 14 forming a support for a cushion 15, which is preferably in the form of a helical spring. The rod is provided with a collar or enlargement 16, and said floor has an opening 70 17 of sufficient size to permit the collar to pass through it. The rod also carries a smaller collar 17^a capable of passing through an opening in a bracket 17^b secured on floor 2 and a weight 17^c, the latter fitting slidingly 75 on the rod and incapable of passing through the opening of said bracket.

When the apparatus is in its initial position the collar 16 is supported upon a catch 18 pivoted on a bracket 19 and held yielding in the path of vertical movement of said collar 16 by a spring 20, a lug 20^a projecting from the bracket 19 preventing catch 18 from being pressed far enough to conflict with the collar 17^a. (See Fig. 2.) A cable 80 21 guided over a sheave 22 is connected to said catch at one end and at its opposite end to a lever 23 mounted on frame 4 within convenient reach in order that an operator may withdraw the catch and permit the rod to 90 drop downward until the collar 16 is arrested by the cushion or by the contact of the plunger 24 with the bran or other feed being packed into the sack.

The plunger 24 is preferably of truncated 95 conical form and secured on the lower end of the rod 13 and is adapted when elevated to form a cut-off or closure for the tapering mouth 8 of the spout 5, and said plunger is provided with a plurality of channels 25 through which air may pass upward in the 100 downward movement of the plunger as the bran or other feed which passes down into the sack when the plunger starts downward will be in sufficient volume to practically fill 105 the space between the exterior surface of the plunger and the sack and unless means were provided for the upward passage of the air,

the latter would in a measure retard the descent of the plunger and interfere with the free descent of the feed, as will be readily understood.

5 At its upper end the plunger rod 13 is equipped with a pivoted extension rod 26 provided with a plurality of spaced pins 27 so as to constitute a rack bar, and said rod 13 and its extension 26 are provided at opposite sides of the pivotal point with collars 28 and 29 respectively. A spring 30 is carried by and exerts pressure in opposite directions on said collars at one side of the pivotal point of the extension rod for the purpose of 10 holding the latter pressed yieldingly toward a shaft 31 suitably journaled in the upper part of the building, which shaft is equipped with a belt pulley 32 driven by a belt 33, and a cam arm 34 adapted to successively engage 15 the pins 27, for a purpose which hereinafter appears.

Secured on a timber 35 or its equivalent adjacent to the belt wheel, is a bracket 36 having inclined arms 37 at opposite sides of extension 26; terminating in flanges 38 interposed between the extension and the shaft 31, to limit movement of the former toward the latter under the pressure of spring 30, and the extension rod is also provided with 20 a pin 39 adapted when the plunger is at its highest point to be forced by a guide arm 37 of the bracket 36 or its equivalent, outward from the shaft and thus hold the lowest pin 27 out of the range of action of the cam arm 34 as shown in Fig. 5.

When the plunger is elevated as shown in Fig. 1, it is held in such position by the catch 18, and at such time the pin-equipped rod extension 26 occupies the position shown 40 in Fig. 5.

Assuming that it is desired to charge the sack with feed, not shown, contained in the hopper or fed continuously thereto when the machine is in operation, through chute 1, the lever 23 is pulled downward to permit the plunger and the parts connected thereto, to drop downward as hereinbefore explained, until the collar 16 is arrested by the cushion 15. The belt is then started and the shaft 45 rotated in the direction indicated by the arrow Fig. 2, it being understood that as soon as the plunger drops, a charge of feed passes through the reduced mouth 8 of spout 5 into the sack, and it will also be noted that when the plunger drops, spring 30 swings the rod extension 26 toward the shaft until arrested by the flanges 38 of guide bracket 36 so that 50 as the cam arm starts upward it will engage the topmost pin 27 and thereby lift the plunger until said cam arm becomes disengaged with said pin, which in practice will 55 preferably be about an eighteen inch lift. In this lifting operation a quantity of the feed will pass down around the plunger to the bottom of the sack. As the cam arm 60

passes out of engagement with said pin, the plunger will drop and the air will pass up through the channels 25 and thus avoid agitating or blowing the feed upward around the plunger. In the next revolution of the 70 cam arm it may reengage the same pin and again lift the plunger, but if it does engage said pin the second lifting operation will be somewhat less than the first because the feed in the bottom of the sack will prevent the 75 plunger from moving downward to its extreme limit of movement as when the sack is empty. In practical operation the cam arm may engage said pin two or three times and eventually the plunger will be elevated 80 until the cam arm engages the next lower pin. These operations are repeated until the undermost pin is engaged and lifted by the cam arm, by which time the sack will be full of packed feed, the final engagement of 85 the cam arm with the undermost pin causing pin 39 to slide upward and outward against guide arms 37 for the purpose of disposing the undermost pin 27 out of the range of movement of the cam arm. The door 10 may then be opened and the sack removed and 90 replaced by an empty one, after which the door is reclosed and the described operations repeated. It will thus be seen that a sack can be rapidly, efficiently and reliably filled. 95

In the operation of the apparatus collar 17^a is functionless if heavy feed is being packed, as in such case the weight 17^c will be removed from the plunger-rod. Where the feed is light and it is desired to pack it 100 as tightly as possible in a sack, the weight 17^c is slipped upon the rod, so that each time the plunger is raised, the small collar 17^a passes up through the bracket 17^b and lifts the weight, to utilize the same for causing the plunger to move downward with greater force than usual. The weight is arrested by the bracket 17^b just before the collar 16 strikes the cushion 15, which is thus relieved 105 of the strain incident to arresting the downward movement of the weight. After sufficient feed has been packed in the sack to check the downward movement of the plunger before the collar 16 strikes the cushion, the power of the downward stroke of the plunger will be increased because the plunger will not move downward a sufficient distance for the weight to come in contact with the bracket 17^b as will be readily understood. 110

It is obvious that the size of the weight 120 17^c may be varied and that the density of the packed feed may be diminished or increased by adjusting collar 16 downward or upward respectively, on rod 13.

From the above description it will be apparent that I have produced a feed packer embodying the desirable features enumerated and I wish it to be understood that I do not desire to be restricted to the exact 125 details of construction shown and described 130

as obvious modifications will suggest themselves to one skilled in the art.

Having thus described the invention what I claim as new and desire to secure by Letters-Patent, is;

1. A feed packing apparatus, comprising a bin having a spout, a downwardly tapering mouth-piece fitting slidingly in the spout, means for securing a sack around the spout, 10 a casing to inclose the sack below the spout, a plunger, and means whereby the plunger may be reciprocated and at intervals attain increasing altitudes, the plunger at or before the end of the last movement engaging 15 and closing the mouth-piece and causing the same to move upward in the spout.

2. A feed packing apparatus, comprising a bin having a spout, a downwardly tapering mouth-piece fitting slidingly in the spout, 20 means for securing a sack around the spout, a casing to inclose the sack below the spout, a plunger, means whereby the plunger may be reciprocated and at intervals attain increasing altitudes, the plunger at or before 25 the end of the last movement engaging and closing the mouth-piece and causing the same to move upward in the spout, and means for automatically securing the plunger in its most elevated position and in engagement with the mouth of said spout.

3. A feed packing apparatus, comprising a bin having a spout, a downwardly tapering mouth-piece fitting slidingly in the spout, means for securing a sack around the spout, 35 a casing to inclose the sack below the spout, a plunger, means whereby the plunger may be reciprocated and at intervals attain increasing altitudes, the plunger at or before the end of the last movement engaging and 40 closing the mouth-piece and causing the same to move upward in the spout, a collar movable with the plunger, a catch for automatically underlying said collar when the plunger has attained its most elevated position, and means for tripping said catch to 45 permit the plunger to drop downward to its most depressed position.

4. A feed packing apparatus, comprising a bin having a spout, a downwardly tapering mouth-piece fitting slidingly in the spout, means for securing a sack around the spout, a casing to inclose the sack below the spout, a plunger, means whereby the plunger may be reciprocated and at intervals attain increasing altitudes, the plunger at or before 55 the end of the last movement engaging and closing the mouth-piece and causing the same to move upward in the spout, a collar movable with the plunger, a catch for automatically underlying said collar when the plunger has attained its most elevated position, means for tripping said catch to permit the plunger to drop downward to its 60 most depressed position, and a cushion to be engaged by said collar in its descent and

support the same and the plunger in their most depressed positions.

5. A feed packing apparatus, comprising a bin having a spout, a downwardly tapering mouth-piece fitting slidingly in the spout, 70 means for securing a sack around the spout, a casing to inclose the sack below the spout, a plunger, a rod extending upward from said plunger through the spout and bin, an extension pivoted to said rod and provided with a series of pins at different altitudes, a shaft provided with a crank arm for successively engaging said pins and raising the plunger predetermined distances, and yielding means for holding the rod extension with its pins 80 in the path of movement of the crank arm.

6. A feed packing apparatus, comprising a bin having a spout, a downwardly tapering mouth-piece fitting slidingly in the spout, means for securing a sack around the spout, 85 a casing to inclose the sack below the spout, a plunger, a rod extending upward from said plunger through the spout and bin, an extension pivoted to said rod and provided with a series of pins at different altitudes, a shaft provided with a crank arm for successively engaging said pins and raising the plunger predetermined distances, yielding means for holding the rod extension with its pins 90 in the path of movement of the crank arm, and means for limiting the movement of the rod extension toward said shaft.

7. A feed packing apparatus, comprising a bin having a spout, a downwardly tapering mouth-piece fitting slidingly in the 100 spout, means for securing a sack around the spout, a casing to inclose the sack below the spout, a plunger, a rod extending upward from said plunger through the spout and bin, an extension pivoted to said rod and provided with a series of pins at different altitudes, a shaft provided with a crank arm successively engaging said pins and raising the plunger predetermined distances, yielding means for holding the rod extension 105 with its pins in the path of movement of the crank arm, and means for overcoming the resistance of said yielding means to cause the rod extension when the plunger is elevated to swing and withdraw its undermost 110 pin from the path of said crank arm.

8. A feed packing apparatus, comprising a bin having a spout, a downwardly tapering mouth piece fitting slidingly in the 120 spout, means for securing a sack around the spout, a casing to inclose the sack below the spout, a plunger, a rod extending upward from said plunger through the spout and bin, an extension pivoted to said rod and provided with a series of pins at different 125 altitudes, a shaft provided with a crank arm successively engaging said pins and raising the plunger predetermined distances, yielding means for holding the rod extension with its pins in the path of movement of the 130

crank arm, means for overcoming the resistance of said yielding means to cause the rod extension when the plunger is elevated to swing and withdraw its undermost pin from 5 the path of said crank arm, means to automatically secure the plunger in its most elevated position, and means to trip said securing means.

9. In a feed packer, a spout adapted to be 10 received by the upper end of a sack, an upwardly tapering plunger provided in its tapering surface with air channels which extend from its under to its upper side, and means for reciprocating the plunger within 15 the spout and sack.

10. In a feed packer, a spout adapted to be received by the upper end of a sack, a downwardly tapering mouth for said spout, a reciprocatory plunger adapted when elevated to close said mouth-piece and provided 20 with air channels in its surface exterior to the mouth-piece when the latter is closed by the plunger.

11. A feed packer, comprising a bin having 25 a spout, a downwardly tapering mouth piece slidable up and down within the spout, means to limit the downward movement of the mouth piece, means for supporting a sack around said spout and pendent therefrom, a casing inclosing the sack, a plunger within the spout below the mouth piece thereof and of materially less diameter than the former and adapted at times to close the mouth piece to the passage therethrough of 30 material to be packed in the sack, means to vertically reciprocate said plunger, a cushion, means movable with the plunger and adapted at times to strike downward upon the cushion and arrest the downward movement 35 of the plunger.

Copies of this patent may be obtained for five cents each, by addressing the "Commissioner of Patents.
Washington, D. C."

12. A feed packing apparatus, comprising a bin having a spout, means for supporting the sack around said spout a casing inclosing the sack, a plunger, means to reciprocate said plunger, a cushion, a weight bearing a 45 movable relation to the plunger, means movable with the plunger to engage and lift the weight, means to at times check the downward movement of the weight before the corresponding movement of the plunger 50 ceases, and means movable with the plunger to engage the cushion at times and limit the downward movement of the plunger.

13. In a feed packing apparatus, a spout, a mouth piece arranged to slide vertically 55 in the spout and of downwardly-tapering form, a plunger for reciprocatory action within the spout below the mouth piece, and means for reciprocating the plunger and causing it at intervals to attain increased 60 altitudes and on its upstroke engage and move the mouth-piece upward in the spout and close said mouth-piece.

14. In a feed packing apparatus, a spout, a mouth piece arranged to slide vertically 65 in the spout and of downwardly tapering form, a plunger for reciprocatory action within the spout below the mouth piece, means for reciprocating the plunger and causing it at intervals to attain increased 70 altitudes and on its upstroke engage and move the mouth piece, and means to secure the plunger in its most elevated position.

In testimony whereof I affix my signature, in the presence of two witnesses.

ROBERT MAXWELL.
